Inventor:

August Prym.

By Marks Clark
Atty's

UNITED STATES PATENT OFFICE.

AUGUST PRYM, OF BUSBACH, NEAR STOLBERG, GERMANY.

PRESS BUTTON.

Application filed May 22, 1922. Serial No. 562,904.

To all whom it may concern:

Be it known that I, AUGUST PRYM, a subject of Germany, and residing at Busbach, near Stolberg, Rhine State, Germany, have 5 invented a certain new and useful Press Button, of which the following is a specification.

This invention relates to improvements in press buttons and more particularly to press 10 buttons of the type which are secured to the supporting material by means which eliminates the necessity of piercing the material or sewing the two halves of the press button in position.

15 The primary object of the invention is to furnish a press button with improved detachable means for securing the two halves of the press button to the supporting material.

20 Another object of the invention is to furnish a detachable means for securing press button halves in position and provided with an operating member to permit said means to be readily detached.

25 With the foregoing objects outlined and with other objects in view which will appear as the description proceeds the invention consists in the novel features herein-after described in detail, illustrated in the 30 accompanying drawing, and more particularly pointed out in the appended claims.

Referring to the drawing:

Figure 1 is a vertical sectional view of a press button socket member showing the 35 improved means for detachably securing the same to the supporting material.

Fig. 2 is a similar view of the ball or head member of the press button.

Fig. 3 is a plan view of a securing spring 40 or resilient member.

Fig. 4 is an elevation of the latter.

The press button halves *a* are provided with annular skirts *b* extending in the direction of the supporting material *d*. Each 45 of these annular skirts is provided with an inwardly extending flange *e* adapted to contact with a securing spring or resilient ring *c* for holding each of the press button halves in engagement with the supporting material *d*. It will be noted that the spring in expanding will force a portion of the supporting material beneath the flange *e* so that 50 each press button half will be securely held

in engagement with the supporting material.

As shown in Figures 3 and 4, the spring member *c* is provided with a loop or finger engaging member *g*, which, in the socket piece, bears on the dome or cap *h* and presses the supporting material thereon. By grasping the part *g* the spring *c* may be readily removed from the press button halves.

From the foregoing it is believed that the construction, operation and advantages of the invention may be readily understood by 65 those skilled in the art, and it is apparent that changes may be made in the construction disclosed without departing from the spirit of the invention as expressed in the claims.

What I claim and desire to secure by Letters Patent is,—

1. In a press button adapted to be secured in position without piercing its supporting material, an edge and a flange bent towards 75 the material, and a freely detachable resilient split ring member holding the material under the said flange, said ring member being contractable in order to permit the same to be removed.

2. In a press button which is secured in position without piercing its supporting material, an edge and a flange which are bent towards the material, an annular spring member holding the material under the said 85 flange and a loop on the spring member, lying in a plane outside the plane of the said flange.

3. In a press button which is secured in position without piercing its supporting 90 material, an edge and a flange, which are bent towards the material, a cap on the socket-piece and a loop on the spring member lying in a plane outside the plane of the said flange and pressing the material 95 against the said cap.

4. In a press button which is secured in position without piercing its supporting material, an edge and a flange which are bent 100 towards the material, a resilient ring member holding the material under the said flange, and a finger engaging member extending from said ring to permit the ring to be readily detached.

5. A press button as claimed in claim 1 105 in which said resilient ring member and fin-

ger engaging member consists of a single piece of wire having the portion intermediate its ends shaped to form a loop, the portions of said wire arranged between the 5 loop and the ends of the wire being curved substantially concentrically with said loop and forming an annular spring, the plane of the main portion of said loop being ar-

ranged above the plane of said annular spring.

In testimony whereof I hereunto affix my signature in the presence of two witnesses.

AUGUST PRYM.

Witnesses:

ALESE TENHAEFF,
JOHANN FRINGS.
